UNITED STATES PATENT OFFICE

ARTHUR B. JOHNSON, OF MINNEAPOLIS, MINNESOTA

TOOL FOR SURFACING AND FORMING FIBROUS MATERIAL

Application filed April 12, 1930. Serial No. 443,679.

My present invention provides a highly efficient tool for shaping and surfacing felted fibrous materials such for example, as the insulating board sold to the trade under the trade name "Insulite" or the insulating board sold to the trade under the name of "Celotex". These insulating materials are made from wood, sugar cane or similar fibrous pulp intertwined and compressed into form of self-sustaining sheets or boards of considerable strength and capable of various uses such, for example, as insulating material in refrigerators and in houses. Such materials are also found of great utility as a substitute for plaster in the interior of houses. This material is primarily manufactured in large sheets having quite rough surfaces and of quite irregular thickness and in application of such fibrous insulating material to its various uses, there is developed a great demand for smaller sheets in the form of strips or panels of uniform thickness with a smooth outer surface and having special forms such as lapped joints, raised panel effects and the like. In the past it has been customary to employ a series of large grinding and sanding drums to dress the material down to a desired thickness and smooth the surface thereof, to trim the material and to cut the same into smaller panels of a desired size by use of circular saws or the like and to bevel the edges thereof when so desired by means of circular saws or knives set to cut at a desired angle. These devices hitherto used have not satisfactorily solved the problem nor made possible the formation of many desirable reductions, bevels, cuts and surfacing of such insulating material.

My invention provides a tool or device which in actual practice has been found to be efficient to cut not only straight bevels and angular grooves, but also desired curved surfaces and to produce very smooth surfaces on the fibrous material. In carrying out my invention in the commercial form above referred to, I employ a large number of circular or disc saws clamped together in compact arrangement so that their teeth cut a continuous extended surface. The saws should not be over one-eighth of an inch in width and preferably they are not over one-sixteenth

of an inch in width and they are set with their teeth staggered so that the surface cutting action of the teeth of the adjacent saws do not cut simultaneously at the same point. For the cutting of flat surfaces, the teeth of the adjacent saws will have their points ground so that they lie in a common cylinder surface, the axis of which is the axis of rotation of the teeth; but for the cutting of beveled surfaces either straight or rounded the teeth of the adjacent saws will be ground off obliquely transversely of the saw planes to correspond to the bevel or outline that is to be cut on the insulating material. Preferably, at intervals, cut-off saws of larger diameter than the surfacing saws are clamped into or against the surfacing saws so that the insulating material may be simultaneously beveled, grooved, surfaced and cut into strips.

In the accompanying drawings, which illustrate the invention, like characters indicate like parts throughout the several views.

Referring to the drawings:

Fig. 1 is an elevation with some parts in section showing the improved tool designed to surface and bevel the fibrous material while cutting the same into strips;

Fig. 2 is a section taken on the line 2—2 of Fig. 1;

Fig. 3 is a fragmentary perspective showing portions of the beveling and cutting saws;

Fig. 4 is an enlarged section taken on the line 4—4 of Fig. 2;

Fig. 5 is a fragmentary perspective showing a portion of one of the strips cut by the tool used as shown in Fig. 1;

Fig. 6 is a fragmentary view showing the staggered arrangement of the two adjacent saws of the tool;

Fig. 7 is a view corresponding to Fig. 6 but showing the teeth of the saws given lateral "set";

Fig. 8 is a view corresponding to Fig. 1, but illustrating a tool arranged with saws for beveling and cutting the insulating material, the saws for surfacing the face thereof being omitted;

Fig. 9 is an end elevation of one of the strips cut by the tool used as in Fig. 8, some parts being broken away;

Fig. 10 is a fragmentary view in vertical section illustrating the action of the tool shown in Fig. 8;

Fig. 11 is a view corresponding to Fig. 1, 5 the outline of the saws forming the tool being indicated diagrammatically but illustrating the line on which they will be ground to form raised panels having rounded portions;

Fig. 12 is a fragmentary section of the tool 10 shown in Fig. 11, the saws being here indicated;

Fig. 13 is an end elevation of one of the 15 panels cut by the tool used as shown in Figs. 11 and 12, some parts being broken away; and

Fig. 14 is a modification showing the saws 15 arranged and applied to form a molding from fibrous insulating material.

Referring first to the construction illustrated in Figs. 1 to 4, inclusive, the numeral 20 15 indicates a mandrel or shaft on which the saws are mounted, the same being clamped together on the mandrel by clamping nuts 16 and washer-like clamping collars 17. The large diameter cut-off saws are indicated by 25 the numeral 18; the saws for cutting a flat surface on the face of the insulating material are indicated by the numeral 19 and the saws for cutting bevels on the edges of the strips of insulating material are indicated by 30 the numeral 20. As best shown in Fig. 4, the points of the teeth of the saws 19 are ground on a cylindrical surface while the points of the teeth of the saws 20 are ground in a conical surface so that they produce straight 35 bevels. The form of strips A cut by the teeth, Fig. 1, is shown in Fig. 5. Very wide sheets of insulating material may be simultaneously cut into any desired number of strips, the strips beveled, the strips dressed down to 40 a desired thickness, and their surfaces smoothed off by one operation. In Figs. 1 and 4, the ragged outside edge portions of the sheet from which the strips are cut off are indicated at a.

45 The insulating strips cut by the teeth, shown in Figs. 8 and 10, are adapted to be tied together to form beveled raised panels with lapped joints but with the unbeveled faces of the panels left in natural condition; 50 and hence this tool comprises only the shaft or mandrel 15^a, cut-off saws 18^a, and bevel cutting saws 20^a, the said saws being clamped together in groups and onto the mandrel by clamping nuts 16^a, washer-like clamping collars 16^b, and nut-acting clamping collars 17^a. The panel or strip cut in Figs. 8, 9 and 10 is 55 designated by the letter B.

In the arrangement shown in Figs. 11 and 60 12, the cut-off saws are indicated at 18^b, the cylindrically ground surfacing saws at 19^b, and the concavely ground beveling saws at 20^b. The form of panel cut as illustrated in Figs. 11 and 12 is marked C.

65 In the arrangement shown in Fig. 14 for cutting a molding out of insulating material,

the cut-off saws are indicated by the numeral 18^c and the concavely and convexly ground saws for giving the molding a complex surface is indicated at 20^c. In Figs. 1, 4, 8, 10, 11, 12 and 14 the character Y indicates a table 70 over which the insulating sheets are fed to the improved tool.

By reference to Figs. 2, 6 and 7, it will be noted that the teeth of the surfacing saws 19 are ground down at their ends to form blunt 75 or rounded surfaces 19^a that conform to the arc of a circle struck from the axis of the saws. In practice I have found that saws having their ends ground down in this manner make a smoother surface on fibrous material than can be produced by sharp pointed saws. The teeth of sharp pointed saws have some tendency to raise the fibers of the material therebehind, leaving a fuzzy appearing 80 surface while the blunted saw teeth cut the surface of the material with their leading edges and then rub the surface of the material with their rounded blunt portions, thus preventing the fibers from raising and producing a kind of polished appearance on the 85 surface of the material.

In practice I have found that the front ends 90 19^a of the saw teeth 19 should, for best results, extend circumferentially of the saws a distance approximately equal to the width of the saw teeth. These approximate proportions of length and width of the blunt ends 19^a of the saw teeth are clearly shown, especially in Fig. 3 of the drawings.

What I claim is:

A tool for surfacing fibrous materials comprising a plurality of toothed disk saws closely clamped together, the teeth of the several saws having blunt ends that conform to the periphery of a circle struck from the axis of the saws and said blunt ends extending circumferentially of the saws a distance substantially equal to the width of the saw teeth.

In testimony whereof I affix my signature. 110
ARTHUR B. JOHNSON.
